UNITED STATES PATENT OFFICE.

HERBERT E. MARKS, OF SEWICKLEY, PENNSYLVANIA.

SKYLIGHT.

Application filed November 22, 1921. Serial No. 516,924.

To all whom it may concern:

Be it known that I, HERBERT E. MARKS, a citizen of the United States, and a resident of Sewickley, in the county of Allegheny and State of Pennsylvania, have invented a new and useful Improvement in Skylights, of which the following is a specification.

This invention relates to roof structures and particularly to that type adapted for 10 sky-lights and other structures having glass or similar transparent sections. Such structure may, however, be used for other purposes.

The object of the invention is to provide a 15 simple, strong, economical and efficient structure for the purpose intended which may be easily and quickly assembled, which offers substantially no obstruction to the flow of water therefrom, which is water-tight and which will compensate for expansion and contraction due to changes in temperature.

In the accompanying drawings Fig. 1 is a 20 perspective view of the preferred embodiment of the invention showing some of the roof sections disposed in place, and with some of the sections removed to disclose the underlying structure; Fig. 2 a transverse sectional view taken on the line II—II of 25 Fig. 1; Fig. 3 a detail plan view of one of the transverse binding strips; Fig. 4 a section taken on the lines IV—IV of Figs. 1 and 3.

The structure consists of the main longitudinal supporting bars 1, transverse binding strips 2 bridging the space between them, and the panes or roof sections 3, preferably formed of glass or other transparent material supported thereby.

The bars 1 are preferably made of standard rolled sections T-shaped in cross section as clearly shown in Fig. 2, and are provided with the vertical web 4 and the lateral seat portions 5. The transverse binding strips are also of inverted T-shape in cross section, as shown in Fig. 4. These strips are provided with oppositely disposed grooves 6 and 7 formed by slitting its central web 8 at intervals and bending the tongue portions 9 intermediate thereof in opposite directions so as to encase the edges of the adjacent panes or roof sections 3, as clearly shown in Fig. 1.

Resting upon said portions 5 and filling 55 the space between the base portions of the transverse strips are sealing strips 10 made

of any suitable material, said strips being of substantially the same thickness as the base portions of the transverse strips, so as to act in conjunction therewith to provide a 60 flat surface upon which the sections 3 are supported.

In building up the structure, the sealing strips 10 are first placed upon the seat portions 5, after which one edge of a pane or 65 section 3 is positioned against the transverse member 2 so that the tongues 9 will embrace the edge thereof with another transverse strip abutting its opposite edge, and the several sections are similarly positioned against 70 a previously positioned section until the entire structure is completed. An impervious yielding compound, such as bituminous cement, is then poured around the edges of the sections so as to completely fill the crevices 75 between the several parts. The tongue portions 9 of the transverse strips encase the edges of sections 3 and hold them in assembled relation. Wedges 11 are driven through apertures 12 located in the web 4, 80 which effectively lock the transverse strips 2 and sections 3 positively in place.

The webs 4 extend but a slight distance above the surface of the sections 3 and the tongues 9 lie in close contact therewith so 85 that substantially no obstructions are presented to hinder the flow of water off the structure. By using a yielding compound for the sealing medium, as above described, not only a water-tight structure is secured 90 but one which will compensate for changes due to expansion and contraction caused by variations in temperature.

It is thus seen that the invention provides a simple, sturdy, inexpensive and efficient 95 structure for the purpose intended, and although the same is described and illustrated as embodied in a sky-light construction it is obvious that the same may be readily employed for structures intended for 100 various uses of a similar nature.

I claim:

1. In a roof structure for sky-lights the combination of a series of spaced longitudinal metallic bars of inverted T-shape in 105 cross section, provided with lateral seat portions and a vertical web, transverse binding strips of similar cross section resting freely at their extremities upon and removably supported by the opposing seat portions of a pair of adjacent longitudinal bars and having channels formed by slitting the web por-

tion at intervals and bending alternate tongues formed thereby in opposite directions embracing the edges of the roof sections, the webs of both said bars and strips 5 facing in the same direction.

2. In a roof structure for sky-lights the combination of a series of spaced longitudinal metallic bars of inverted T-shape in cross section provided with lateral seat portions and a vertical web, transverse binding strips of similar cross section resting freely at their extremities upon and removably supported by the opposing seat portions of a pair of adjacent longitudinal bars and having 10 channels formed by slitting the web portion at intervals and bending alternate tongues formed thereby in opposite directions embracing the edges of the roof sections, the webs of both said bars and strips 15 facing in the same direction, and a yielding impervious sealing compound filling the crevices between the parts whereby to provide a water-tight structure and to compensate for expansion and contraction therein.

25 3. In a roof structure for sky-lights the combination of a series of spaced longitudinal metallic bars of inverted T-shape in cross-section provided with lateral seat portions and a vertical web, transverse binding 30 strips of similar cross section having oppositely disposed channels formed by bending alternate portions of its central web in opposite directions embracing the edges of adjacent roof sections and resting freely at its 35 extremities upon and supported by the opposing seat portions of a pair of adjacent longitudinal bars whereby rendering the same removable therefrom, the webs of both 40 said bars and strips facing in the same direction, a sealing strip of substantially the same thickness as the base portion of said transverse binding strips resting upon said seat portions and extending between said base portions to form a substantially flat 45 supporting surface for the roof sections.

4. In a roof structure for sky-lights the combination of a series of spaced longitudinal metallic bars provided with lateral seat portions and a vertical web, transverse binding strips having oppositely disposed grooves embracing the edges of adjacent roof sections and resting freely at its opposite extremities upon and supported by the opposing seat portions of a pair of adjacent longitudinal bars, a sealing strip of substantially 50 the same thickness as the base portion of said transverse binding strips resting upon said seat portions and extending between said base portions, and locking wedges 55 extending through apertures in the vertical web and contacting the transverse strips to 60 position the same.

65 5. In a roof structure for sky-lights the combination of a series of spaced longitudinal metallic bars of inverted T-shape in

cross section, provided with lateral seat portions and a vertical web, transverse binding strips of similar cross section having oppositely disposed grooves formed by bending alternate portions of its central web in 70 opposite directions embracing the edges of adjacent roof sections and resting freely at its extremities upon and supported by the opposing seat portions of a pair of adjacent longitudinal bars whereby rendering the 75 same removable therefrom, a sealing strip of substantially the same thickness as the base portion of said transverse binding strips resting upon said seat portions and extending between said base portions, and locking wedges extending through apertures in 80 the vertical web and contacting the transverse strips to position the same.

6. In a roof structure for sky-lights the combination of spaced longitudinal metallic 85 bars of inverted T-shape in cross section provided with lateral seat portions and a vertical web, transverse binding strips having oppositely disposed grooves formed by bending alternate portions of its central web 90 in opposite directions so as to contact the upper surface and encase the edges of adjacent roof sections, said transverse strips having their opposite ends resting upon and removably supported by the seat portions of 95 adjacent longitudinal bars, a sealing strip positioned upon the seat portions and filling the space between the transverse strips, means for locking the said strips in place, and a yielding impervious sealing compound 100 filling the crevices between the parts whereby to provide a water-tight structure and to compensate for expansion and contraction therein.

7. In a roof structure for sky-lights the combination of a series of spaced longitudinal metallic bars provided with lateral seat portions and a vertical web, transverse binding strips having oppositely disposed grooves embracing the edges of adjacent 105 roof sections and resting freely at its opposite extremities upon and supported by the opposing seat portions of a pair of adjacent longitudinal bars, a sealing strip of substantially 110 the same thickness as the base portion of said transverse binding strips resting upon said seat portions and extending between said base portions, a yielding impervious sealing compound filling the crevices 115 between the parts, whereby to provide not only a water tight structure but to compensate for expansion and contraction therein and locking wedges extending through apertures in the vertical web and contacting the transverse strips to position the same.

In testimony whereof, I sign my name.

HERBERT E. MARKS.
